COMBINED HANDBAG AND LOOSE LEAF RING BINDER

Herbert S. Chase, Woodmere, N. Y., assignor to Bernard Cahn Co., Inc., New York, N. Y.

Application June 19, 1957, Serial No. 46,641

Term of patent 7 years

(Cl. D87—5)

Figure 1 is a front elevational view of a combined handbag and loose leaf ring binder showing my new design in a closed position;

Figure 4 is a front elevational view, drawn to a smaller scale, showing the design in an open position, and

I claim:

The ornamental design for a combined handbag and loose leaf ring binder, substantially as shown, and described.
